US00D951329S

(12) **United States Design Patent** (10) **Patent No.:** **US D951,329 S**
Zhan (45) **Date of Patent:** **** May 10, 2022**

(54) **WEARABLE CAMERA**

(71) Applicant: **SHENZHEN PA. TIMES TECHNOLOGY CO., LTD**, Shenzhen (CN)

(72) Inventor: **Jingyun Zhan**, Shantou (CN)

(73) Assignee: **SHENZHEN PA. TIMES TECHNOLOGY CO., LTD**, Shenzhen (CN)

(**) Term: **15 Years**

(21) Appl. No.: **29/729,342**

(22) Filed: **Mar. 25, 2020**

(30) **Foreign Application Priority Data**

Nov. 26, 2019 (CN) 201930653677.9
